HOT WATER HEATED HOVER

Perry S. Martin, Harrisonburg, Va., assignor to
Shenandoah Manufacturing Company, Harrisonburg, Va., a corporation of Virginia

Application July 31, 1929, Serial No. 382,379

14 Claims. (Cl. 119—34)

This invention relates to hovers and has for its principal object the provision of a conical hover which may be heated by hot water or by steam and in which the ventilation is improved so that the crowding of the chicks is minimized.

In hover construction the public has become accustomed to the conical shape and while this shape is not as effective as other shapes its popularity makes it essential that manufacturers produce at least one model of this type. It is simple indeed to heat a conical hover if a flexible peripheral wall be used to hold in the air. While this works satisfactorily in some ways, it has many inherent disadvantages, and the production of the requisite heat in the hover while still having plenty of ventilation is a problem which heretofore has not been satisfactorily solved. One requirement is that the heat be not confined to the radiating surfaces for it is easily possible otherwise to have the condition arise wherein those chicks nearest to the heating element are kept sufficiently warm while other chicks are so chilled as to cause fatality. The present hover piping is so located that one at least of the pipes creates a zone of high temperature against the wall of the house so as to prevent crowding of the chicks toward the darker rear of the enclosure.

In the drawing:—

Figure 1 is an elevation largely in section.

Figure 2 is a plan view of the coil and the air inlet housing.

Figure 3 is a transverse section through a poultry house in which the system is installed.

Figure 4 is a detail in a vertical cross section thru the tank.

Referring first to Figures 1 and 2, the main heat supply pipe whether hot water or vapor communicates with the hover inlet pipe 10 thru a fitting 11 which may be a T or and L and the inlet pipe in turn is threaded into the cap or closure 14 of the tank 15, the latter consisting of an upper chamber 16 and a lower chamber 17 separated by a central partition 18 thru which there may be a small orifice 19 so that hot water for example may pass slowly from the upper compartment 16 to the somewhat larger lower compartment 17 irrespective of the usual communication between the compartments.

The lower cap 20 carries a nipple having threaded engagement with a T 21 leading to the fluid outlet pipe 22 connected thru the T 23 with the return main 24. The air intake 25 extends some little distance beyond the edge of the conical hover 26, is open at its receiving end 27 and merges into a central cylindrical casing 28 quite

larger in diameter than the lower cap 20 so that an annular opening is provided surrounding the tank 15 and the air that passes thru this annular opening is preheated in passing for the distance of the air inlet casing 25 along the horizontal water outlet pipe 22.

The normal means of communication between the upper and lower chambers of the tank is thru the tubes 30 radially disposed about the tank each having an upper relatively straight slightly sloping portion 31 and a lower portion 32 also straight but sloping down at a materially greater angle and these two portions are connected at their outer ends by an integral portion 33 circumferentially disposed, relatively short and disposed at an angle greater than the downward tilt of the arms 31 but preferably less than the downward tilt of the radial arms 32. I prefer that the center of the short portion 33 shall be at the level of the central partition or diaphragm 18.

The hover 26 is conical and of such size as to require a space between the circumference of the tube portions and the inner wall of the hover. About halfway up the cone I secure a disk 34 which forms the ceiling of the hover space and provides with the upper portion of the cone a dead air space 35. Preferably I strengthen the rather thin wall of the disk 34 by a disk 36 of wood or other heat insulating material. A central perforation is provided in this circular insulating member to receive an upwardly extending integral sleeve 37 from the metal disk 36, which sleeve rather snugly receives the vertical hot water inlet pipe 12 on which it is slidable.

At its apex the hover or cone 26 is riveted as at 38 to a collar 40 having ears 41 in which are received supporting chains 42 by means of which the hover cone can be raised and lowered, depending upon conditions and when the proper adjustment has been made, the collar 40 may be secured to the vertical pipe 10 by means of the thumb screw 43.

In operation the cone is lowered to the proper height and the heating fluid is admitted thru the pipes 10 as controlled by the valve 12. Assuming that water is used this entirely fills the upper chamber 16 and passes thru each of the tubes 30 simultaneously outwardly thru the slightly tilted arms 31 then slightly downward in a substantially annular path adjacent the side of the cone 26 thru the short portions 33 and returning by the downwardly and inwardly directed sloping arms 32 which are also radially arranged but which are not in vertical alinement with the inlet of the arm 31 as best seen in Figures 2 and 55

4. The more sharply tilted arms 32 discharge into the lower chamber 18 which also receives a quantity of hot water thru the by-pass opening 19. The return pipe 22 and the return main 24 5 obviously lead to a heater which is not shown.

Referring now particularly to Figure 3 which is a sectional elevation thru a poultry shed or house showing the relative location of the hover and the rear wall. The space toward the rear wall 46 is naturally darker and the chicks frequently crowd into this darkened corner which normally would be considerably colder than under the hover and because of the coldness the chicks crowd to an improper degree. This I avoid 10 by placing the return pipe 24 in the corner and if I use a vapor line the inlet main 47 is placed just above the return line 24 and over both I place a slanting screen of wire gauze 48 to prevent access. 15

20 The return pipe 24, or both pipes as illustrated, create a zone of high temperature against the rear wall 46 of the house and this entirely obviates crowding of the chicks at that point since there is plenty of heat in that zone. With the 25 vapor line I may use a vertical pipe 44 and a substantially horizontal pipe 45 to lead to the L 11 but in case I use hot water I must place the inlet main at a higher elevation as will be readily understood.

30 While it is not at all essential so to do I prefer to have the height of the cylindrical casing 28 such that in the lowest position of the cone 26 the sloping pipe sections 32 will rest upon this annular wall and I also may extend the air in- 35 take 25 thru the screen 48. While it would be better theoretically to make the tubes 30 of copper I do not find it advantageous from a practical standpoint to use this more expensive material and in my recent output I have used iron 40 pipe 30 and weld them into the tank and I also find that I can weld in the caps or disks 14 just as conveniently and cheaply as to provide caps which have threaded engagement with the tank walls; furthermore by thus welding all of these 45 parts together I secure a much longer trouble-free life for the device.

The construction shown is an improvement over the provision of a solid radiating element as by virtue of the radial disposition of the tubes 50 30, a plurality of spaces are provided for the circulation of the air, and the chicks on the ground are warmed by direct radiation from the upper 55 arms 31, as well as from the lower arms 32 in just the same way that sensible heat is directly radiated from an old fashioned hearth. In addition, the lower surface of the disk 34 and its integral downwardly turned flange are polished in order to reflect downward the heat radiated from the upper arms 31 of the tubes.

60 There is naturally a blanket of hot air formed beneath the ceiling wall of the cone, and this discharges annularly about the edge 45 of the cone, but upward radiation from the pipes 32 is not lost as it would be in a solid element, because not only can the pipes radiate directly down but the upper radiation is reflected down to the ground by the mirror bottom of the disk 34, which it will be noted somewhat snugly fits 65 the pipe 10 and with the collar 40 serves to avoid all wobbling of the cone. The fresh air is delivered centrally and is warmed not only by radiation from the disk 35 but by contact with the tubes or pipes 30 and by the body of the 70 tank 15.

What I claim is:

1. In a brooder, a conical hover, means for raising and lowering said hover, a tank located centrally of said hover, a diaphragm in said tank dividing same into two chambers, means for conveying heated fluid to one of said chambers and for delivering fluid from the other of said chambers, and a plurality of pipes connecting said chambers, portions of each of said pipes being approximately radial with respect to the axis of 10 said conical hover.

2. A heater for a conical hover consisting of an upright cylindrical tank having a diaphragm therein intermediate its two ends, a plurality of tubes connecting the opposite ends of said tank, 15 each of said tubes consisting of a section sharply bent in elevation, the ends of said tubes being substantially radially disposed with the bent sections equispaced.

3. In combination, a conical shaped hover 20 herein called a cone, an air tunnel having its discharge coaxial with said cone, a supply pipe passing thru the apex of the cone, a return pipe within said tunnel, and a plurality of tubes connecting said pipes, each tube consisting of two arms 25 substantially radially disposed with respect to the axis of the cone and making a small acute angle with one another in elevation and joined by a short integral section at the vertex of said angle.

4. In combination, a conical hover, a plurality 30 of elongated spaced similar hot water heating elements substantially radially positioned with respect to the axis of the hover and equispaced within the hover, means for heating and conveying fresh warm air to the center of the hover, 35 means for reflecting the heat from said elements, and means for connecting said elements to a hot water supply.

5. The device of claim 4 in which the heating 40 elements are metal tubes, each tube comprising two portions connected together adjacent the periphery of the hover, said portions sloping upwardly and downwardly respectively from their peripheral connections toward the axis of the hover.

6. A heating element for a hover consisting of a substantially U-shaped tube having a short central section and two relatively long sections each joining the short section at approximately a right angle, said short section and one of said 50 long sections determining a plane and said other long section making an angle with said plane.

7. The device of claim 1 in which the diaphragm is perforated whereby to allow continued circulation of the heated fluid through circuits 55 formed by said tank and said pipes after said fluid conveying means is shut off.

8. In a poultry house having a rear wall and a floor, a hover near the rear wall thereof, an inlet main, a central heating pipe in said hover in communication with said main, a return main along the junction of the rear wall and floor providing a zone of high temperature on the floor near the hover, means connecting the central pipe with the return main, and means for conveying ventilating air along said connecting means to a point beneath the hover.

9. In a poultry house having a rear wall and a floor, a hover near the rear wall thereof, an inlet main, a central heating pipe in said hover in communication with said main, a return main along the junction of the rear wall and floor providing a zone of high temperature on the floor near the hover, means connecting the central pipe with the return main, means for conveying ventilating 70 75 75

air along said connecting means to a point beneath the hover and means for raising and lowering said hover.

10. In combination, an upright conical hover herein called a cone, means for raising and lowering said cone, a supply pipe passing thru the apex of the cone and means for adjustably fixing said cone to the pipe at any desired height, a plurality of elongated spaced heating elements approximately radially positioned and equispaced within the cone, and means surrounding said supply pipe for reflecting the heat from said elements.

11. The device of claim 10 in which the reflecting means divides the cone into two portions, the upper portion forming with the top of the cone a dead air space.

12. A heater for a conical hover consisting of an upright cylindrical tank having a diaphragm therein intermediate the two ends, a plurality of substantially U-shaped tubes connecting the opposite ends of said tank, one end of each of the bases of said U-shaped tubes lying in substan-

tially the same plane, said plane being at right angles to the axis of said tank and slightly below a plane passing thru the points of connection of the tubes with the upper end of the tank, and the other ends of said bases being slightly below said plane whereby the downward slope of each tube is continuous throughout its length.

13. A heater for a hover, consisting of a plurality of chambers in superposed relation, a plurality of separate tubes connecting said chambers, each of said tubes having a central bend therein and two substantially straight end portions, the end portions of the tubes being disposed approximately radially about said chambers.

14. In a brooder, a conical hover, a supply pipe, said conical hover being mounted on said pipe, a return pipe, and a plurality of tubes beneath said hover and each connecting said pipes, a portion of each of said tubes being substantially radially disposed with respect to the axis of said hover.
